UNITED STATES PATENT OFFICE.

WALTER MYERS, OF BRIDGEPORT, CONNECTICUT, ASSIGNOR TO THE SINGER MANUFACTURING COMPANY, A CORPORATION OF NEW JERSEY.

ORNAMENTAL-STITCH SEWING-MACHINE.

1,239,715.

Specification of Letters Patent. Patented Sept. 11, 1917.

Application filed December 3, 1914. Serial No. 875,210.

To all whom it may concern:

Be it known that I, WALTER MYERS, a citizen of the United States, residing at Bridgeport, in the county of Fairfield and State of Connecticut, have invented certain new and useful Improvements in Ornamental-Stitch Sewing-Machines, of which the following is a specification, reference being had therein to the accompanying drawings.

This invention relates to improvements in attachments for embroidery or ornamental stitch sewing machines and has for its object to provide improved means for effecting circularly arranged designs.

In the accompanying drawings, which form a part of the specification, Figures 1, 2 and 3 are views in front side elevation, plan and rear side elevation respectively, of one form of ornamental stitch sewing machine equipped with the present invention. Figs. 4, 5 and 6, a sectional view of the needle vibrating mechanism including the switch-cam carried by the main-shaft; a perspective of the needle vibrating segment-lever and a like view of the needle vibrating segment-lever-carrier, respectively, the latter view including the switch-cam follower. Fig. 7, a plan view of the cloth-plate, together with the spur carrying slide-plate. Fig. 8, an under side view of Fig. 7. Fig. 9, an end view of Fig. 7, a portion of the bed-plate being added in section. Fig. 10, a perspective of the slide-plate securing lever. Fig. 11, a perspective of one of the slide-plate retaining brackets provided with bearings for the securing lever. Fig. 12, views illustrating the character of the circular ornamental designs effected by the present construction.

The present invention is shown as applied to a Singer ornamental stitch sewing machine, the same as is represented by my United States Patent No. 1,135,959, April 13, 1915.

Referring to the figures, 1 represents the bed-plate of the sewing machine upon which is mounted the bracket-arm comprising the standard 2 and arm bracket 3, 4 the main- or needle-bar driving shaft provided at its rear end with the hand- or band-wheel 5 and at its opposite end with the take-up cam 6, 7 the sewing needle, 8 the needle-carrying-bar operatively connected by the link 9 with said take-up cam, the needle-

carrying-bar 8 being mounted in suitable bearings formed in the swinging gate 10 journaled on pintle screws, as 11, in a manner common to earlier constructions, 12 the take-up lever, 13 thread-tension and 14 the thread-controller.

15 represents the lower or looper actuating shaft operatively connected at its rear end by suitable quartering cranks, as 16, with the main-shaft 4, its opposite end being 65 provided with a flange 17 connected by link 18 with the crank 19 carried by the gear-shaft 20 provided with the gear-member 21 operatively connected with a like gear-member 22 carried by the loop-taker driver 23, 70 thus transmitting stitch-forming movements to the loop-taker 24, as in earlier constructions.

25 represents one form of commonly employed switch-cam into which tracks a 75 follower 26 journaled in a suitable bearing 27 preferably formed integral with the segment-lever carrier 28, which latter is provided with a hollow shaft 29 journaled in a suitable bearing 30 formed in 80 the bracket-arm, the rear end of said shaft being provided with a suitably secured collar 31 to hold said shaft against accidental endwise movement. 32 denotes a segment lever provided with a hollow 85 shaft 33 journaled in the hollow shaft 29, a segmental guide-slot 34, arcuate slot 35, notch 36 and spring-controlled plunger 37 provided with a seat 38 which registers with one or the other of the openings 39 or 40 90 formed in the segment lever carrier 28, dependent upon the character of the seam or figure desired.

Into the hollow shaft 33 is slidably mounted a plunger 41 provided at one end 95 with an enlarged oval head 42, its opposite end being threaded to receive the screw 43 whose slotted head 44 is arranged on the side of the driving wall 45, formed integral with the shaft 33, opposite to that of its 100 threaded end, thus permitting endwise movements of said plunger of substantially the length of the body portion of said screw, a spring 46 confined between said slotted head and the screw 47, acting to hold the plunger 105 41 in its outward position as shown in Figs. 2 and 4. 49 denotes a sleeve secured by screw 50 to the rear end of the hollow shaft 33, and between the enlarged portion 51 of said sleeve and the collar 31 carried by the 110

shaft 29 is confined the spring 52 which normally acts to hold the segment lever 32 in operative relation with its carrier 28, for a purpose later to be explained.

53 represents a bracket secured by screws, as 54, to the bracket-arm, 55 a rock-shaft journaled in suitable bearings formed in said bracket and onto said shaft is mounted to move endwise a yoke 56 provided with a 10 crank-arm 57 carrying a cam-plate 58, said yoke being secured to turn with said shaft by a teated screw 59 threaded into said yoke and entering a suitable slot (not shown) formed into said shaft, a cam lever 60 pivoted on a suitable pin (not shown), passing 15 through said shaft, acting in opposition to the resiliency of the spring 61 to move said yoke toward the rear side of the machine, thus carrying said cam-plate out of effective 20 relationship with the head 42 of the plunger 41, for a purpose later to be explained.

62 represents an oscillating shaft crank suitably secured upon the shaft 55 and at its free end provided with a stud-screw 63 25 which tracks a slot 64 formed in the segment lever slide connection 65, the lower end of the latter being provided with a suitable opening (not shown) through which extends a stud 66 threaded into the slide 30 block 67 tracking the segmental guide-slot 34, said stud also acting as the pivotal connection for one end of the swinging gate connection 68, the opposite end of the latter being pivotally connected to the swinging gate 35 10 by a suitable ball joint connection 69.

70 represents a segmental slide block stop adjustably secured in the guide-slot 34, the wing nut 71, threaded onto the stud 66, acting to secure the slide block 67 in given 40 adjustment when it is desired to effect successive zigzag stitches of a given amplitude of needle vibration, a spring 72 attached at one end to the shaft crank 62 and at its opposite end to the connection 65 acting to 45 normally hold the stud 63 at the lower end of the slot 64.

73 represents a thread tension releasing crank-arm suitably secured to the rock-shaft 55, said crank-arm, together with the shaft 50 50 crank 62, acting to secure said shaft against accidental endwise movement, the crank arm being provided with a depending arm lug 74 which, when depressed, acts on the end of the tension stud 75 to move the latter 55 in opposition to the resiliency of the flat spring 76 and coiled spring 77, thus lessening the degree of tension exerted by said latter spring on the tension disks, as 78.

To the front end of the crank-arm 73 is 60 pivotally attached one end of a link 79 whose opposite end is pivotally attached to a rock-lever 80 journaled on a stud 81 threaded into the arm bracket, and to the opposite end of said rock-lever is pivotally 65 attached, by stud-screw 82, a hub 83 into

which is threaded the upper end of a treadle-actuated rod 84 which, in practice, is operatively connected with a suitable treadle (not shown), a spring 85 acting to normally hold, through the connections previously pointed out, the axis of the stud 66 in alinement with the axis of the hollow shaft 33. 86 represents one form of commonly employed spring depressed cloth-presser carrying bar provided at its lower 75 end with a cloth-presser 87.

When it is desired to stitch a figure of uniform stitches, the operator adjusts and by wing nut 71 secures the slide 67 to effect the desired amplitude of vibration of the 80 needle, and during the stitching operation the fabric is manually turned under the needle and if in the stitching of the design it is desired to effect the ordinary seam, the operator moves the cam-lever 60 to its vertical position, thus permitting the spring 61 to move the cam-plate 58 in line with the head 42 of the plunger 41 when the operator, through the manipulation of a suitable treadle, rocks the shaft 55 which causes the 90 cam-plate 58 to move the plunger 41, and through the medium of spring 46 and nut 47, move the segment lever toward the operator a distance sufficient to release the teat 38 from engagement with the opening 40 95 and with the stationary lug 88 in engagement with the notch 36 formed in said segment lever, thus holding the latter out of engagement with the segment lever carrier and with the needle in its outside or depth 100 stitch position or in position to form the ordinary seam, after which the operator returns the lever 60 to its former position, it being understood that radial stitches of varying lengths may be employed through 105 the manipulation of a suitable treadle connected, as previously described, with the rock-shaft 55, it being understood that the spring 46 when depressed is of sufficient strength to overcome the strength of the 110 spring 52.

Referring to the inventive features new to the present construction, 89 represents a cloth-plate secured upon the bed-plate by pin 90 and catch-lever 91, the free end 92 115 of the latter yieldingly contacting the under side of the bed-plate, as shown in Fig. 9 to hold said cloth-plate against accidental displacement. 93 denotes an eyelet spur secured in a plate 94 slidably mounted in the 120 cloth-plate and provided with a needle slot 95 extending out from the eyelet spur needle opening 96, the plate 94 being secured in sliding relationship with the cloth-plate by bearing brackets 97 and 98 and flange bearings 99 and 100 of the cloth-plate and plate 94 respectively. 101 denotes a slide-plate securing lever provided with teats or raised portions, as 102, and mounted to oscillate in the opening 103 in the bracket 97, the open- 130

ings, as 104, in the latter coacting with the teats to permit of the adjustment of the slide-plate, the moving of said teats into engagement with the inclines, as 105, acting 5 to secure said slide-plate in given adjustment. The present construction comprehends the employment of interchangeable slide-plates provided with such size of eyelet-spur as is essential to the design of 10 the product.

To effect design *a* of Fig. 12, the operator loosens the wing nut 71, thus leaving the slide-block 67 free to be moved, through the connections pointed out, in the guide- 15 slot 34 by the manipulation of the treadle, previously referred to, the sequence of stitch-forming movements with respect to the eyelet-spur being as follows:—Suppose the eyelet-spur to be positioned to receive 20 the needle when forming the left hand stitch, as viewed by the operator, the latter places the fabric on the cloth-plate with the spur extending up through the opening 106, when through the manipulation of the 25 treadle, the needle is controlled to effect lateral movements to form the stitches 107 as the fabric is manually rotated about the spur, followed by an adjustment of the slide-plate 94 to the left to position the fabric for 30 the stitching of the circular design 108. To effect the circular design 108, the operator moves the cam-lever 60 to its vertical position permitting the spring 61 to move the cam-plate 58 in line with the head 42 of the 35 plunger 41 when the operator, through the manipulation of the treadle, rocks the shaft 55 which causes the cam-plate 58 to move the plunger 41, and through the medium of spring 46 and screw 47, move the segment 40 lever toward the operator a distance sufficient to release the teat 38 from engagement with the opening 40 and effect its adjustment in the opening 39 which causes the needle, when forming zigzag stitches to be 45 moved laterally equidistant across the axis of the spur as first positioned when, through the manual manipulation of the treadle, the needle is given lateral movements of varying degrees of amplitude as the fabric is being turned about the fabric spur.

To effect the circular design 110, the segment lever 32 is returned to its right hand position for effecting the eyelet 107, thus placing the zero stitch at the left, the lo-

cating of the right hand stitch dependent 55 upon the amplitude of lateral movement given the needle. The circular design 111 is formed as in the stitching of the design 108. Design *b* of Fig. 12 will be readily understood from the method described for 60 the stitching of design *a*, and that the un- stitched sections are effected by bringing the needle to rest, turning the fabric the required distance and trimming out the 65 threads leading from one to the other of the separate series of stitches.

From the foregoing it will be understood that many designs can be effected and by the employment of different colored threads adapt the designs to fabrics of different 70 texture, color, weight and weave.

Having thus set forth the nature of the invention, what I claim herein is:—

1. In a sewing machine for ornamental stitching, the combination with a stitch- 75 forming mechanism including a needle having stitch-forming movements in different paths, of a slide-plate provided with a fabric spur having a needle opening and a needle slot extending out from said opening 80 in a direction corresponding to the lateral movements of said needle and adjustable to permit of the placing of circularly arranged zigzag stitches outside the field occupied by said spur.

2. In a sewing machine for ornamental stitching, the combination with a stitch- 90 forming mechanism including a needle having stitch-forming movements in different paths, of a cloth-plate and a slide-plate carried by the latter, said slide-plate being provided with a fabric spur having a needle opening and a needle slot extending out from said opening in a direction corresponding to the lateral movements of said needle 95 and adjustable to permit of the placing of circularly arranged zigzag stitches outside the field occupied by said spur, and means for securing said slide-plate against accidental movement.

In testimony whereof, I have signed my name to this specification, in the presence of two subscribing witnesses.

WALTER MYERS.
